(57) CLAIM

We claim the ornamental design for a three door container lid, as shown and described.

DESCRIPTION

FIG. 1 shows a front, top, right side perspective view of a three door container lid with all doors in the closed position; FIG. 2 shows a front view of FIG. 1; FIG. 3 shows a back view of FIG. 1; FIG. 4 shows a left side view of FIG. 1; FIG. 5 shows a right side view of FIG. 1; FIG. 6 shows a top view of FIG. 1; FIG. 7 shows a bottom view of FIG. 1; FIG. 8 shows a front side view of the three door container lid of FIG. 1 with a lid main door shown open 90 degrees; FIG. 9 shows a back side view of FIG. 8; FIG. 10 shows a left side view of FIG. 8; FIG. 11 shows a right side view of FIG. 8; FIG. 12 shows a top view of FIG. 8; FIG. 13 shows a bottom view of FIG. 8; FIG. 14 shows a front side view of the three door container lid of FIG. 1 with two side lid doors shown open 90 degrees; FIG. 15 shows a back side view of FIG. 14; FIG. 16 shows a right side view of FIG. 14; FIG. 17 shows a left side view of FIG. 14; FIG. 18 shows a top view of FIG. 14; FIG. 19 shows a bottom view of FIG. 14; and, FIG. 20 shows a front side view of the three-door container lid of FIG. 1 installed on an exemplary container. The broken lines in FIG. 20 illustrating a container depict environment and form no part of the claimed design. All other broken lines depict portions of the three door container lid that form no part of the claimed design.

1 Claim, 20 Drawing Sheets
